ANTENNA ARRANGEMENT

Andrew Alford, New York, N. Y., assignor to Federal Telephone and Radio Corporation, a corporation of Delaware

Application March 23, 1942, Serial No. 435,885

15 Claims. (Cl. 250—33)

This invention relates to improvements in antenna devices, and in particular to such arrangements as are used in airplanes for receiving horizontally polarized waves from all directions. This is a preferred type antenna for radio range use in accordance with my application, Serial No. 303,206, filed November 7, 1939, in plane-to-plane communication, etc. Under these circumstances, there is no particular need for a completely circular characteristic, nor that polarization be only horizontal. Prime considerations are rather that the antenna be small, light, simple and relatively rugged.

It is accordingly an object of the invention to provide an improved antenna meeting the above requirements.

Another object is to provide an improved type of generally non-directional antenna for operation at relatively short wavelength.

A further object is to provide an improved antenna, the performance of which will be relatively unaffected by changing weather conditions, such as rain, ice formation, etc.

A more specific object is to provide an improved ultra short wave antenna having no insulators or other relatively weak members at points of structural stress.

Other objects and further features of novelty and invention will hereinafter be pointed out or will become apparent to those skilled in the art from a reading of the following specification in connection with the drawing attached hereto. In said drawing—

Fig. 1 is a plan view of a preferred embodiment of the invention;

Fig. 2 is a side elevation of the embodiment of Fig. 1;

Fig. 3 is a graphical representation of a horizontal characteristic of the antenna of Figs. 1 and 2;

Figs. 4 and 5 schematically illustrate alternative embodiments of the invention; and

Figs. 4a and 5a graphically depict characteristics of the respective embodiments of Figs. 4 and 5.

In order to meet the above noted requirements for simplicity and ruggedness, I propose that the structural parts of a non-directional airplane antenna be assembled in a unit construction entirely of metal. Such a structure forms the preferred embodiment of the invention shown in Figs. 1 and 2. According to this embodiment, the antenna comprises two radiating elements 10, 11 which have a length preferably one-quarter the wave-length at the operating frequency and

are joined to each other at one end. If arms 10 and 11 were to make an angle of 180° with respect to each other, the resultant characteristic of the antenna would be in the nature of a figure of 8, as obtained from a dipole a half wavelength long. However, as indicated above, it is an object to provide an antenna which is generally non-directional in character. Accordingly, arms 10 and 11 make an angle less than 180° with each other, and, in the preferred form shown, this angle is in the neighborhood of 80°. This preferred angle is the result of a compromise, for the less the spread of arms 10 and 11 the more the characteristic approaches circularity. However, with such improvement in the characteristic the radiation resistance decreases and proper tuning of the unit becomes more critical.

Arms 10 and 11 are supported by a strut member 12 rigidly mounted to the fuselage 13 of the aircraft and supporting arms 10 and 11 substantially at their point of juncture. In order that the characteristic of the antenna may be essentially responsive to horizontally polarized energy, arms 10 and 11 lie in a plane which is normally horizontal, namely, a plane generally parallel with the wings of the aircraft. Thus, the entire antenna unit comprising arms 10 and 11 and support 12 may be made as a single welded structure and securely fastened to the aircraft.

In order suitably to couple the antenna elements 10, 11 to wave-translating means within the aircraft (not shown), a pair of conductors 14, 15 extend in insulated relation through a hollowed portion of the strut 12 and pass out near the trailing edge thereof to be connected respectively to arms 11 and 10. Conductors 14 and 15 are connected to arms 10 and 11 at points spaced a certain amount from the neighborhood of juncture of these arms in order that an appropriate match between the antenna impedance and the characteristic impedance of the transmission line formed by conductors 14, 15 may be made.

In an actual embodiment of the device just described which was designed to operate at frequencies of the order of 100 megacycles, the characteristic impedance of the line formed by conductors 14 and 15 was 160 ohms, and a spacing of six inches was found preferable as the distance from the vertex of the V formed by arms 10 and 11 to the point of connection of conductors 14 and 15 to arms 11 and 10. It is clear that with such a connection, the portion of arms 10 and 11 extending out from the point thereon

at which the coupling conductors are connected, operate as an antenna, and the remainder of arms 10 and 11 adjacent the vertex of the V operate as building-out sections for the above-noted impedance-matching purposes. The characteristic of such an antenna is roughly shown by the diagram of Fig. 3 from which it may be seen that a minimum is obtained normal to the direction of flight, but that the ratio $a:b$ of maximum to minimum characteristic is of the order of 2.5:1. The antenna is thus of a generally non-directional nature. It is to be noted that the pattern of Fig. 3 represents the characteristic of the antenna comprising arms 10 and 11 by themselves as energized in the manner indicated, that is, without considering any effects of the presence of the aircraft fuselage 13. It is clear however that if the fuselage 13 is metallic, it may act as an attenuator in the general direction of flight to make the ratio of maximum to minimum characteristic approach 1:1. In this manner, a roughly circular characteristic is obtained. This attenuating effect of the fuselage 13 of course depends largely upon the spacing between the antenna and the nearest conductive surface of the fuselage. As this spacing is decreased, the attenuating effect increases, and I have found that a very nearly circular characteristic may be obtained (with antenna arms a quarter wavelength long and an angle of 80° as above specified) when this spacing is 10 inches or, more generally, when the spacing is about 0.08 to 0.09 of a wave-length.

In order to promote rigidity of the antenna structure and to decrease its resistance to wind, arms 10 and 11 are preferably of streamline section and taper downwardly from the vertex of the V. Structure 12 is also streamlined and for lightness and rigidity is preferably hollow. A length to breadth ratio of 3:1 for cross-sections of members 10, 11 or 12, is preferable for streamlining purposes.

The strut 12 is suitably capped by member 16 faired with the streamlining in strut 12, and conductors 14 and 15 are led out of strut 12 at the rear through insulation ports 17, 18. Conductors 14 and 15 are thus situated symmetrically with respect to ground potential (strut 12 and portions of arms 10, 11 adjacent thereto), and, due to this fact, the active antenna elements 10, 11 may be supported directly by means of metal-to-metal connections, there being no need for insulation of any kind at this point of structural stress.

Even though the antenna would seem to be relatively critical with respect to its characteristic for several frequencies it has been found that with the above described 100 mc. design, operation is perfectly satisfactory without any need of modification of the antenna or its connections at both 96 and 104 mc. The mismatches which are introduced by a deviation in frequency from the frequency for which the antenna is designed to operate introduce losses affecting both the desired signal and any noise picked up. When the losses thus introduced are not very large, and the antenna is used for reception, the receiver automatic volume control is able to make up for these small differences so that no appreciable effect is noted on the range of localizer or other signals being picked up.

Under certain circumstances, it may be desirable that the airplane antenna exhibit a still more nearly circular inherent radiation characteristic, such as for example, when the fuselage

is not of metal so that it cannot be as good an attenuator of radiant energy in the direction of flight. In such case, I provide antennae as shown in Figs. 4 or 5.

5 The form shown in Fig. 4 comprises two arms 20, 21 again disposed so as to be normally horizontal in flight and each of overall length equal substantially to a quarter of the operating wavelength. In this embodiment, however, each arm 10 is formed with three straight sections at angles to each other. The entire antenna structure thus approximates the shape of a loop. Referring to Fig. 4a, the characteristic of the modification of Fig. 4 is seen substantially to approach circularity.

In the further embodiment of Fig. 5, the antenna again comprises two arms 30, 31, disposed in a plane which is normally horizontal in flight and substantially a quarter wave-length long. 20 Arms 30, 31 are, however, provided with one less bent section than the arms of the antenna of Fig. 4, for purposes of greater rigidity. It will be noted from the radiation characteristic for this latter form (see Fig. 5a) that there is a greater departure from a circular characteristic and something half way between the characteristic of the V antenna of Fig. 1 and circularity is obtained.

It is to be noted that the horizontal characteristic of an antenna of any of the above-described natures on an airplane is not a uniquely defined quantity because this characteristic is always a function of the angle of bank of the airplane. An approximation of the horizontal characteristic may be obtained if the airplane is flown in a large circle, that is, without any appreciable bank, but best results may be obtained by flying over the same location from different directions while a received signal is being measured. If the airplane be flown in a tight circle, say with a 30° bank, a wholly different characteristic is obtained because a wing may get in the way, that is, between the transmitter and the antenna to reduce the received signal strength normal to the direction of flight by as much as 15 decibels. A characteristic thus obtained would have to be qualified with the statement that it is for a 30° bank.

50 In the above discussion, reference was made to the compensation effect of a metallic fuselage on the V antenna characteristic. The fuselage itself and not the wing is, of course, meant; and the resultant approximately circular characteristic thus obtained has reference to the usual flying conditions of zero bank. Since no means have been found for automatically compensating for the increased attenuating effect of the wing as the angle of bank is increased, the zero bank characteristic must be sufficiently full on the sides, or approximately circular, so that with a given angle of bank, the wing will not so attenuate the characteristic (due to the above-noted blanking effect) in directions generally normal to the direction of flight, that response in this direction is below a tolerable minimum.

70 In the above described embodiments wherein the attenuating effect of the fuselage of the plane is relied upon to make the overall characteristic of the antenna approximate circularity, it is to be understood that the antenna is placed on the side of the airplane remote from the wing. For example, if the airplane is a low-winged monoplane, the antenna should be mounted on top of the fuselage whereby the fuselage attenuation may predominate. If in this type plane

the antenna be mounted below the fuselage, the wing has a greater attenuating effect on the characteristic normal to the direction of flight than the fuselage has on the characteristic in the direction of flight, thus making for an even greater ratio of maximum to minimum characteristic. On the other hand, if the airplane be a high-winged monoplane, it is preferable to install the antenna below the fuselage whereby the fuselage attenuating effect may predominate to yield a characteristic approaching circularity. Of course, in the case of a center-winged craft, substantially no difference in characteristic is obtained if the antenna be installed above or below the fuselage.

It is clear that I have described an extremely simple antenna device suitable for ultra-short-wave use, whether for transmission or reception, and that with relative ease, a relatively uniformly non-directional characteristic may be obtained therewith. The structure exhibits electrical advantages in that it is relatively unaffected in its performance under adverse weather conditions such as in rain or when ice forms. It is clear that if any ice should form, this formation would be on the leading edge of members 10, 11 and 12, particularly strut 12, and that under the circumstances, no additional leakage is formed since the juncture of strut 12 and arms 10 and 11 is conductive, and, hence, of the same potential. Aerodynamically, the structure has the advantages that it may be relatively easily adapted to streamlining and that there are few parts to offer resistance to flight. From a structural point of view as above indicated, the antenna may be made highly rigid and strong with light-weight materials. A preferred material from which to construct strut 12 and arms 10 and 11 is beryllium-copper alloy sheet because of its highly excellent resiliency and resistance to tiring in the presence of vibration. Furthermore, as also pointed out above, rigidity is enhanced by the fact that all structural parts may be metallically interconnected, the only required insulator being at a point of no structural stress.

Although I have described the above preferred embodiments of my invention as including antenna arms of one or more straight sections, it is to be understood that curved members of approximately equivalent form may be employed to yield substantially equivalent characteristics. For example, the embodiment of Fig. 4 could include two continuously arcuate arms each a quarter wave-length long, and substantially the characteristic of Fig. 4a would result.

Furthermore, while I have described the V angle preferably to be substantially 80°, satisfactory results may be obtained within as wide limits as 40° to 120°. Satisfactory results may also be obtained by adjustment of the antenna between 0.07 and 0.15 of a wave-length above the fuselage, and of the point of connecting the conductors 14, 15 so as to be 0.02 to 0.06 of a wave-length from the junction of arms 10 and 11 and support 12. As explained above, these quantities should be adjusted for each type installation to obtain the desired characteristic.

Although I have described my invention in detail in particular connection with the preferred forms illustrated, it is to be understood that many modifications, additions and omissions may be made within its scope as defined by the appended claims.

What is claimed is:

1. An antenna arrangement having a given radiation characteristic in a given plane, comprising a supporting member, two arms forming a single V antenna in said plane the apex of said V terminating on said member, said arms being rigidly connected to said supporting member toward one end thereof, and means for energizing said arms.
10. 2. An antenna arrangement having a generally non-directional characteristic in a given plane comprising a supporting member, two conductive arms of a length equal substantially to a quarter wavelength at the operating frequency of said antenna arrangement, said arms forming a single V antenna extending in said plane, said arms being rigidly supported toward one end thereof at substantially the same point on said member, and means for energizing said arms at points thereon equally spaced from the point of rigid support.
15. 3. An antenna arrangement having a generally non-directional characteristic in a given plane, comprising a hollow supporting member, two conductive arms of a length equal substantially to a quarter wave-length at the operating frequency of said antenna arrangement, said arms forming a single V antenna extending in said plane and being rigidly connected to said supporting member at substantially one end thereof, and means for energizing said arms at points thereon equally spaced from the point of rigid connection, said energizing means including within said supporting member conductor means further extending from one end of said supporting member to said equally spaced points.
20. 4. An antenna arrangement according to claim 3, wherein said arms are substantially straight.
25. 5. An antenna arrangement according to claim 3, wherein said arms are substantially straight and make an angle less than 180° with each other in said plane.
30. 6. An antenna arrangement according to claim 3, wherein said arms include a portion on one arm making an angle less than 180° with a corresponding portion of the other arm.
35. 7. An antenna arrangement having a generally non-directional characteristic in a given plane, comprising a hollow supporting member, two conductive arms of a length equal substantially to a quarter wavelength at the operating frequency of said antenna arrangement, said arms extending in said plane and being rigidly connected to the supporting member at substantially one end thereof, a portion of one arm making an angle less than 180° with a corresponding portion of the other arm, each of said arms including a further portion, each said further portion being substantially parallel with the other, and means for energizing said arms at points on said arms equally spaced from the point of rigid connection, said energizing means including within said supporting member conductor means further extending from one end of said supporting member to said spaced points.
40. 8. An antenna arrangement having a generally non-directional characteristic in a given plane, comprising a hollow supporting member, two conductive arms of a length equal substantially to a quarter wavelength at the operating frequency of said antenna arrangement, said arms extending in said plane and being rigidly connected to the supporting member at substantially one end thereof, a first portion on one arm making an angle less than 180° with a first portion on the
45. 9. An antenna arrangement having a generally non-directional characteristic in a given plane, comprising a hollow supporting member, two conductive arms of a length equal substantially to a quarter wavelength at the operating frequency of said antenna arrangement, said arms extending in said plane and being rigidly connected to the supporting member at substantially one end thereof, a first portion on one arm making an angle less than 180° with a first portion on the
50. 10. An antenna arrangement having a generally non-directional characteristic in a given plane, comprising a hollow supporting member, two conductive arms of a length equal substantially to a quarter wavelength at the operating frequency of said antenna arrangement, said arms extending in said plane and being rigidly connected to the supporting member at substantially one end thereof, a first portion on one arm making an angle less than 180° with a first portion on the
55. 11. An antenna arrangement having a generally non-directional characteristic in a given plane, comprising a hollow supporting member, two conductive arms of a length equal substantially to a quarter wavelength at the operating frequency of said antenna arrangement, said arms extending in said plane and being rigidly connected to the supporting member at substantially one end thereof, a first portion on one arm making an angle less than 180° with a first portion on the
60. 12. An antenna arrangement having a generally non-directional characteristic in a given plane, comprising a hollow supporting member, two conductive arms of a length equal substantially to a quarter wavelength at the operating frequency of said antenna arrangement, said arms extending in said plane and being rigidly connected to the supporting member at substantially one end thereof, a first portion on one arm making an angle less than 180° with a first portion on the
65. 13. An antenna arrangement having a generally non-directional characteristic in a given plane, comprising a hollow supporting member, two conductive arms of a length equal substantially to a quarter wavelength at the operating frequency of said antenna arrangement, said arms extending in said plane and being rigidly connected to the supporting member at substantially one end thereof, a first portion on one arm making an angle less than 180° with a first portion on the
70. 14. An antenna arrangement having a generally non-directional characteristic in a given plane, comprising a hollow supporting member, two conductive arms of a length equal substantially to a quarter wavelength at the operating frequency of said antenna arrangement, said arms extending in said plane and being rigidly connected to the supporting member at substantially one end thereof, a first portion on one arm making an angle less than 180° with a first portion on the
75. 15. An antenna arrangement having a generally non-directional characteristic in a given plane, comprising a hollow supporting member, two conductive arms of a length equal substantially to a quarter wavelength at the operating frequency of said antenna arrangement, said arms extending in said plane and being rigidly connected to the supporting member at substantially one end thereof, a first portion on one arm making an angle less than 180° with a first portion on the

other arm, a second portion on each said arm, each said second portion being substantially parallel with the other, and a third portion on each arm, said third portions making an angle less than 180° with each other, and means for energizing said arms at points on said arms equally spaced from the point of rigid connection, said energizing means including within said supporting member conductor means further extending from one end of said supporting member to said spaced points.

9. An antenna arrangement having a generally non-directional characteristic in a given plane, comprising a hollow supporting member, two conductive arms of a length equal substantially to a quarter wavelength at the operating frequency of said antenna arrangement, said arms extending in said plane and being rigidly connected to said supporting member at substantially one end thereof, a portion of one of said arms making an angle of substantially 80° with the corresponding portion of the other of said arms, and means for energizing said arms at points on said arms equally spaced from the point of rigid connection, said energizing means including within said supporting member conductor means further extending from one end of said supporting member to said spaced points.

10. An antenna arrangement having a generally non-directional characteristic in a given plane, comprising a hollow supporting member, two conductive arms of a length equal substantially to a quarter wavelength at the operating frequency of said antenna arrangement, said arms extending in said plane, said supporting member and said conductive arms being of streamlined cross-section, said arms being rigidly connected toward one end thereof to said supporting member at substantially one end thereof, and means for energizing said arms at points on said arms equally spaced from the point of rigid connection, said energizing means including within said supporting member conductor means further extending from one end of said supporting member to said spaced points.

11. An antenna arrangement having a generally non-directional characteristic in a given plane, comprising a hollow supporting member, two conductive arms of a length equal substantially to a quarter wavelength at the operating frequency of said antenna arrangement, said arms extending in said plane and being rigidly con-

nected to said supporting member at substantially one end thereof, said supporting member and said conductive arms being of streamlined cross-section, the cross-section of each of said conductive arms tapering down from said rigid connection, and means for energizing said arms at points on said arms equally spaced from the point of rigid connection, said energizing means including within said supporting member conductor means further extending from one end of said supporting member to said spaced points.

12. An aircraft antenna arrangement for operation in the neighborhood of a given ultra-short wave-length comprising a strut member of conductive material extending generally vertically of the aircraft, a pair of antenna elements disposed in a plane corresponding to a horizontal plane when the aircraft is in normal flight, said antenna elements being galvanically inter-connected and rigidly supported toward one end thereof by said strut member and having portions thereof making an angle less than 180° with each other, each said element having an overall length of substantially a quarter of said wave-length, and means for coupling said elements to a wave-translating means, said coupling means including a pair of conductors within said strut member, said conductors extending out the end of said strut members opposite the aircraft and being galvanically associated with said elements at points spaced from the point of support of said elements by said strut member.

13. An antenna arrangement according to claim 12, wherein said points of said galvanic association are spaced from said point of support a distance on the order of 0.02 to 0.06 of said wave-length.

14. An antenna arrangement according to claim 12, for aircraft having a fuselage of conductive material wherein said point of support is spaced from said fuselage a distance on the order of 0.07 to 0.15 of said wave-length.

15. An antenna arrangement according to claim 12, for aircraft having a fuselage of conductive material wherein said point of support is spaced from said fuselage a distance of the order of 0.07 to 0.15 of said wave-length, and wherein said strut member extends from a portion of said fuselage relatively remote from the wings of the aircraft.

ANDREW ALFORD,
